DRAWER CLOSURE ASSEMBLY

Alfred R. Mounce, Fort Wayne, Ind., assignor to
 General Electric Company, a corporation of
 New York

Application December 18, 1948, Serial No. 66,033

6 Claims. (Cl. 312—150)

1

My invention relates to storage cabinets and the like and particularly to such cabinets which are provided with drawers and sealed closures for the drawer openings.

It is sometimes necessary to provide a seal about the drawer openings in storage cabinets and the like. For example, when articles to be refrigerated are stored in drawers it is necessary that a suitable gasket or other seal be provided about the drawer opening to minimize leakage of heat into the refrigerated space. It is a common practice to provide a resilient gasket of rubber or other suitable material about the drawer opening in a position such that it is pressed between the drawer closure and the storage structure. In order to secure an adequate seal by means of a resilient gasket it is necessary to maintain the gasket under pressure. On hinged doors, such as those provided on household refrigerator cabinets, a single latch with a suitable compressing mechanism is commonly provided to secure the required gasket pressure; however, when the entire closure member can move bodily toward and away from the cabinet, as in the case of drawer closures, it is difficult to secure an adequate seal. Accordingly, it is an object of my invention to provide a storage cabinet or the like having an improved drawer and closure for the drawer opening which will maintain the closure member in contact with the drawer opening on all sides thereof.

It is another object of my invention to provide a storage cabinet having a drawer and an improved closure member for the drawer opening which may be latched by a single element at one side of the closure member and will provide sufficient pressure on a door gasket about the opening to secure adequate sealing.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawings in which Fig. 1 is a sectional elevational view of a portion of a storage cabinet provided with a drawer and closure assembly embodying my invention; Fig. 2 is an enlarged sectional view taken along the line 2—2 of Fig. 1; Fig. 3 is a view similar to Fig. 1, with the drawer closure shown in its open position; and Fig. 4 is a view similar to Figs. 1 and 3 of the lower portion of the drawer and structure showing the drawer partially withdrawn from the cabinet.

2

The cabinet illustrated in Fig. 1 comprises a sheet metal structure including an outer metal casing 10 and an inner metal liner 11 spaced apart to provide an intermediate space for the usual thermal insulation and having an insulating breaker strip 12 extending between the case and liner to close the space therebetween along the edges of the cabinet structure, the breaker strip 12 as shown being that about a drawer opening 13. The opening 13 provides communication with a compartment 14 within which is mounted a sliding storage receptacle or drawer 15 having slide members 16 for engaging guides (not shown) mounted in any suitable manner on the 15 compartment walls. A second drawer 17 having a guide 18 is mounted in the upper portion of the compartment 14. The drawer opening 13 is sealed when the drawers are within the compartment by a door or closure member 19 having a 20 resilient gasket 20 of rubber or similar material secured thereto for engagement with the breaker strip 12 about the drawer opening. The closure member is supported on a bracket 21 welded or otherwise suitably secured to the drawer 15. For 25 purposes later to be described, the member is pivotally mounted on the drawer by bolts 22 on opposite sides of the drawer, only one of these bolts being visible in the drawing. As shown in detail in Fig. 2, the bolt 22 passes through two 30 collars or bushings 23 and 24 mounted in the bracket 21 and a bracket 25 respectively, the bracket 25 being welded or otherwise secured to the closure member 19 and the collars 23 and 24 being rotatable with respect to the bolt 22 and 35 each other so that the member 19 may pivot freely with respect to the drawer 15. The bolt 22 is provided with a nut 26, a washer 27, and a lockwasher 28. In Fig. 2 a portion of the front 40 wall of the drawer 15 is indicated at 29. The closure member 19 comprises an outer sheet metal cover 30 and an inner sheet or liner 31 secured together about their peripheries and spaced apart by a portion of the gasket 20 to minimize leakage of heat from the member 30 to 45 the member 31. A handle 32 is provided for moving the drawer, and a push button 33 is provided to actuate a latch mechanism 34 and withdraw a latch bolt 35 so that the closure member is released from a retaining catch 36 mounted on the 50 cabinet.

When the closure member 19 is latched in position, as shown in Fig. 1, the gasket 20 is maintained in contact with the breaker strip 12 entirely around the opening 13 by the force of 55 tension springs 37 near the two edges of the drawer and connected between brackets 38 on

the drawer 15 and lugs 39 on the member 19 plus the horizontal component of force exerted by the latch bolt. The springs 31, only one of which can be seen in the drawing, bias the member 19 in a counterclockwise direction about the pivot 22 and when the drawer is in its closed position the springs 31 are stressed and hold the lower edge of the gasket 20 under pressure; the force of the springs acting about the pivot 22 and against the catch 36 urges the drawer into the cabinet. The spacing of the closure member 19 and the breaker strip 20 when the bolt 35 is in engagement with the catch 36 is such that the compression of the gasket 20 along its top edge is substantially the same as that along its bottom edge, as determined by the pressure of the springs 31 and the adjustment of the catch. Thus the entire gasket is maintained under substantially equal pressure and an effective seal of the drawer opening is secured. When the catch is released the closure member 19 rotates in a counterclockwise direction about the bolt 22 until an arm 40 engages a downwardly turned rear portion of a stop member 41 secured to the bottom of the drawer 15. This prevents direct contact between the bottom of the drawer and the closure member 19 so that there is no impact between these members which might result in damage to the finish of the drawer and closure member. In a similar manner, the extent of clockwise rotation of the member 19 is limited by a downwardly turned portion of the stop 41 at the forward end thereof. This decreases the probability of impacts between the upper drawer 17 and the closure member 19 and also limits the stress on the spring 31. When the closure member 19 is drawn forward it moves from the position of Fig. 3 to a position such as that shown in Fig. 4 in which the drawer is accessible. Also, in this position the drawer 17 may, of course, be moved outwardly and its contents made accessible.

During the operation of the drawer assembly the handle 32 is gripped and the button 33 pressed when the drawer is in the position shown in Fig. 1. This releases the catch whereupon the drawer may be moved forwardly, the closure member rotating until the arm 40 hits the rear portion of the stop 41. This tilting movement which facilitates the adequate sealing of the gasket by allowing the required functioning of the spring 31 also provides increased room for access to the drawer 15 since the upper end of the closure slopes forwardly. The drawer may be returned to its closed position merely by pushing the member 19 forwardly until the bolt 35 is fixed past the catch 36 and latches in the usual manner of operation of spring bolts.

My closure member or door sealing arrangement as described provides a simple and effective seal for sliding storage assemblies and avoids the necessity of providing special devices on the sliding guides, or double latches, or similar arrangements for securing gasket pressure.

While I have shown my invention as applied to a refrigerated storage cabinet, other applications will readily be apparent to those skilled in the art. I do not, therefore, desire my invention to be limited to the particular structure illustrated and described, and I intend by the appended claims to cover all modifications within the spirit and scope of my invention.

What I claim as new and desire to secure by Letters Patent of the United States is:

1. A storage cabinet or the like having a compartment therein and an opening providing access to said compartment, a drawer mounted on said

cabinet for movement into and out of said compartment through said opening, a closure member for said opening pivotally mounted on said drawer on a transverse axis intermediate the edges of the opening and being tiltable about said axis with respect to said drawer, means for biasing said closure member about said axis toward said drawer on one side of said axis whereby on movement of said drawer toward its position within said compartment said closure member first contacts said cabinet adjacent the side of said opening on said side of said axis and is tilted about said axis on further movement of said drawer, and means for latching said closure member in position on said cabinet to close said opening and to retain said member in its tilted position in opposition to said biasing means.

2. A storage cabinet or the like having a compartment therein and an opening providing access to said compartment, a drawer mounted on said cabinet for movement into and out of said compartment through said opening, a closure member for said opening pivotally mounted on said drawer on a transverse axis intermediate the edges of the opening and being tiltable about said axis with respect to said drawer, means for biasing said closure member about said axis toward said drawer on one side of said axis whereby on movement of said drawer toward its position within said compartment said closure member first contacts said cabinet adjacent the side of said opening on said side of said axis and is tilted about said axis on further movement of said drawer, and latching mechanism including complementary elements on said closure member and cabinet and positioned on the other side of said axis and remote therefrom for retaining said drawer within said cabinet and for maintaining said closure member in position on said cabinet to close said opening.

3. A storage cabinet or the like having a compartment therein and an opening providing access to said compartment, a drawer mounted on said cabinet for movement into and out of said compartment through said opening, a closure member for said opening pivotally mounted on said drawer on a transverse axis intermediate the edges of the opening and being tiltable about said axis with respect to said drawer, a spring engaging said drawer and said closure member for biasing said closure member about said axis toward said drawer on one side of said axis whereby on movement of said drawer toward its position within said compartment said closure member first contacts said cabinet adjacent the side of said opening on said side of said axis and is tilted about said axis on further movement of said drawer, and latching mechanism including complementary elements on said closure member and cabinet and positioned on the other side of said axis and remote therefrom for retaining said drawer within said cabinet and for maintaining said closure member in position on said cabinet to close said opening.

4. A storage cabinet or the like having a compartment therein and an opening providing access to said compartment, a drawer mounted on said cabinet for movement into and out of said compartment through said opening, a closure member for said opening pivotally mounted on said drawer on a transverse axis intermediate the edges of the opening and being tiltable about said axis with respect to said drawer, stops for limiting the extent of tilting movement of said closure member in both directions to prevent striking of

said member against said drawer in the open position thereof, means for biasing said closure member about said axis toward said drawer on one side of said axis whereby on movement of said drawer toward its position within said compartment said closure member first contacts said cabinet adjacent the side of said opening on said side of said axis and is tilted about said axis on further movement of said drawer, and means for latching said closure member in position on said cabinet to close said opening and to retain said member in its tilted position in opposition to said biasing means.

5. A storage cabinet or the like having a compartment therein and an opening providing access to said compartment, a drawer mounted on said cabinet for movement into and out of said compartment through said opening, a closure member for said opening pivotally mounted on said drawer on a transverse axis intermediate the edges of the opening and being tilttable about said axis with respect to said drawer, a tension spring connected between said drawer and said member on the bottom side of said drawer to bias said member about said axis toward the bottom of said drawer whereby on moving said drawer toward its position within said compartment said member first contacts said cabinet on the bottom side of said opening and is tilted about said axis to approach the top side of said opening, and latching mechanism including complementary elements on said closure member and cabinet and positioned on the upper side of said closure member and remote from said axis for retaining said drawer within said cabinet and for maintaining

said closure member in position on said cabinet to close said opening.

6. A storage cabinet or the like having a wall member forming a compartment and provided with an opening affording access to said compartment, a drawer mounted on said cabinet for movement into and out of said compartment, a closure member for said opening pivotally mounted on said drawer on a transverse axis intermediate the edges of the opening and being tilttable about said axis with respect to said drawer, a resilient gasket mounted on one of said members for sealing said opening in the closed position of said drawer, means for urging said closure member about said axis toward said drawer on one side of said axis whereby on movement of said drawer toward its position within said compartment said gasket is first pressed between said members along the side of said opening on said side of said axis and said closure member is tilted about said axis on further movement of said drawer to press the entire gasket into engagement with both members, and means for latching said members together in the closed position of said drawer to retain said gasket in sealing engagement with both said members.
